UNITED STATES PATENT OFFICE.

JOSEPH T. L. LAVAGETTO, OF PORTLAND, OREGON.

WOODEN SHIP CONSTRUCTION.

1,390,912.

Specification of Letters Patent. Patented Sept. 13, 1921.

Application filed January 8, 1919. Serial No. 270,208.

To all whom it may concern:

Be it known that I, JOSEPH T. L. LAVAGETTO, a citizen of the United States, and a resident of Portland, county of Multnomah, State of Oregon, have invented a certain new and useful Improvement in Wooden Ship Construction, of which the following is a specification.

My invention relates to wooden ship construction, and the objects of my invention are the following:

To make the ship more permanently water-tight. To make the ship of greater strength by reinforcing the hull in parts on the exterior with bars and sheeting of steel, thereby stiffening the vessel and protecting the hull from injury by impact and undue wear. To this end I so arrange the seams of the planking and the lower part of the ship that the opposing forces created by the weight of the latter and the counter pressure of the sea will have a tendency to compress the seams and keep them closed. And I so arrange the planking of the upper part of the hull as to resist the penetration of the waves dashed up by the sea and shed the water therefrom from the upper part of the ship's sides.

Another object of my invention is to provide a wooden ship construction which shall be economical in the use of lumber for building the ship's sides.

I attain these and other incidental features hereinafter described by the construction illustrated in the accompanying drawings, in which;

Figure 1 represents a side elevation of a vessel embodying all the features of my invention;

Fig. 2 is a larger-scale elevation of the bow of the vessel, illustrating the application of the diagonal steel bars for reinforcing the hull;

Fig. 3 is a partial transverse section representing the arrangement of the planking in the lower and the upper parts of the hulls;

Fig. 4 is a sectional detail of the stem of the ship; and

Fig. 5 is a detail in cross section similar to Fig. 3, but in this instance illustrating the sides of the ship construction of the inner and outer courses or planks.

The frame of the ship, represented by *a*, may be of any convenient construction. On

the upright frame members or ribs are bolted the planks inclosing the sides of the ship. These planks I arrange preferably as shown in Figs. 3 and 5.

Having reference to Fig. 3, the planks, *b*, of the lower part of the hull are of rhomboid cross section so as to have oblique overlapping faces forming the seams in the sides. These seams are arranged as shown, in order that the weight of the ship and the counter pressure of the sea shall create opposing forces having a tendency to compress the seams and keep them closed. The described construction may extend for two-thirds of the height of the hull from the bottom up. The diagonal seams so created also are adapted to hold the oakum more securely in place.

In the upper part of the vessel I use planks arranged as at *c*, also of rhomboid cross section, but with the seams pointing downward; the purpose of which is to better adapt the upper part of the sides of the ship to resist the penetration of the waves dashed up against it by the sea and to more effectively shed the water.

In Fig. 5 I have shown a modification with regard to the construction and arrangement of the planking covering the sides of the ship. In this case the planking comprises inner and outer courses. The inner course *d* may be of the usual construction, but the outer course should be made of planks arranged as described with respect to the parts *b* and *c* of Fig. 3. By building the sides of the vessel of inner and outer courses, as described, not only is the hull strengthened, but, as I believe, the factor of making the hull water-tight is increased.

Furthermore, in constructing ship's sides in the manner illustrated in Fig. 5, I deem it preferable that the opposed faces of the inner and outer courses be left rough, as it has a tendency to give them a better contact. The inner course *d* may be thoroughly oiled and a coating of tar interposed between the opposed faces of the inner and outer courses.

The end seams of the planking at the exterior of the ship are to be well calked and covered with diagonal steel bars *f*, preferably arranged as shown in Figs. 1 and 2, and sunk into the sides of the vessel, so that their outer face will be flush with the outer face of the plank. By this construction a

smooth exterior is provided for the ship's sides, and the headway of the vessel is not in any wise impeded.

As will be noted from Fig. 2, by the use 5 of steel bars, *f*, I may use short lengths of lumber for forming the sides of the ship. The diagonal steel bars *f*, by overlapping the 10 end seams of the planks, not only hold the calking in the end seams in place, but also prevent the end seams from springing loose 15 from any cause. Said steel bars also stiffen the ship and protect its sides from injury due to impact with wharves or other vessels. The steel bars may have a width of 12" to 18" and a thickness of $\frac{1}{8}$ of an inch, but these are merely suggestions.

In order to further strengthen the vessel, I prefer to inclose the exterior of the sides at the ends, bottom and top, as shown in 20 Fig. 1, the sheeting being made of steel plates *g*. And I deem it preferable that the steel plate at the top and sides be ar-

ranged so as to overlap the rail, as shown at *h* in Fig. 3. And at the bow of the vessel the steel plates overlap the stem *i*, as 25 shown at *j*, the overlapping plate portions being covered by the shoe *l*, secured by a bolt *m*. See Fig. 4. The sheeting *g* is to cover the ends of the bars *f*, as at *n*.

All surfaces of the planks covered by the 30 bars or the plates should be well coated with oil or tar before covering with the bars or plates.

Details not described do not have a direct bearing on my invention and may be ar- 35 ranged according to the judgment of the builder.

I claim:

In a wooden-ship hull, the combination of a frame, a covering of planks, and metal 40 bars extending diagonally across the outer faces of the sides of the planks, to cover the end seams of the planking.

JOS. T. L. LAVAGETTO.
